UNITED STATES PATENT OFFICE.

GEORGE B. N. TOWER, OF NEW YORK, N. Y., ASSIGNOR OF ONE-HALF TO
EDWARD L. LAMBIE, OF WASHINGTON, DISTRICT OF COLUMBIA.

STEAM-PUMP.

SPECIFICATION forming part of Letters Patent No. 258,157, dated May 16, 1882.

Application filed February 9, 1882. (No model.)

To all whom it may concern:

Be it known that I, GEORGE B. N. TOWER, a citizen of the United States, residing at New York city, in the county of New York and State of New York, have invented certain new and useful Improvements in Steam-Pumps; and I do hereby declare the following to be a full, clear, and exact description of the invention, such as will enable others skilled in the art to 5 which it appertains to make and use the same. This invention relates to certain new and useful improvements in steam-pumps, more especially designed for forcing water up in buildings where there is not sufficient head for that 10 purpose; and to this end the invention consists in novel features of construction and combination and arrangement of parts, all as will be hereinafter fully described, and set forth in the 15 claims hereto annexed.

Referring to the accompanying drawings, which form a part of this specification, Figure 1 represents a top view or plan of my improved pump; Fig. 2, a side elevation, partly in section, of the same.

In the drawings, A represents a cast-iron supporting-frame, provided on one side and near its ends with suitable transverse bearing-boxes, B B, closed by suitable caps, b b, within which boxes are arranged suitable hollow trunnions, 20 c d, formed or cast integral with the steam and water cylinders C D, having their open ends closed by slotted and screw-threaded caps e' d', through which the pistons for said cylinders move.

E and F represent the respective pistons for said steam and water cylinders C D, and which pistons are connected at their outer ends by suitable slotted lugs, e f, with the crank-pin g of the crank G, journalled in a suitable bearing 25 or box, h, of the supporting-frame, and carrying at its outer end the balance or fly wheel H. The trunnioned steam-cylinder is provided with steam inlet and exhaust ports a a', that are adapted to alternately register with the 30 corresponding ports, a a', leading to a steam-chest, for admitting and exhausting steam from said cylinder as it is oscillated; and the water-cylinder is also provided with similar ports, a² a³, registering alternately with inlet and outlet ports, for admitting and discharging the

water therefrom as said cylinder is oscillated. i i represent suitable packing-rings arranged around said trunnions c d, which can be readily removed when worn and replaced by new ones by simply removing the caps b b of the bearing-boxes B B for the trunnions.

The operation of my improved pump is as follows: The several parts of the pump occupying the position shown in Fig. 2, with the steam-piston at nearly the end of its forward stroke and the water-piston at nearly the end of its backward stroke, the exhaust-ports are nearly registered for exhausting the steam from its cylinder, with the inlet-ports nearly registered for admitting water to its cylinder, and upon a slight further movement of the steam and water cylinders in their oscillations produced by the movement of their pistons, in connection with the momentum of the fly or balance wheel, the steam-cylinder will be exhausting its steam and the water-cylinder admitting water thereto, which action of the water on the piston in the water-cylinder, in connection with the momentum of the fly or balance wheel, will force the pistons simultaneously in the same directions or simultaneously in opposite directions in their respective cylinders, which, at the end of the above strokes of said pistons, will oscillate their cylinders sufficiently to allow their ports to register for the admission of steam to the steam-cylinder and the discharge of water from the water-cylinder.

It will be observed that by the above-described construction of pump I obviate the use of valves, as the trunnioned cylinders form in themselves the necessary valves for closing the ports; and, further, I am enabled to utilize what head of water there may be, in connection with the momentum of the fly or balance wheel, in giving the return-stroke to the steam-piston and the forward or outward stroke to the water-piston, whereby but little steam is required in operating the steam-pump and the condensing of steam avoided.

It will be observed that all parts of my improved steam-pump may be or are formed from cast-iron, and which can be easily and quickly fitted together, thus forming a cheap and durably-constructed pump, which is very effective in operation.

It will be observed that the trunnioned cylinders forming in themselves the necessary valves, said valves must have a positive movement due to the simultaneous movement of the cylinder. No doubt the engine and pump would stop if it were not for the movement of the fly or balance wheel and any pressure from the head of the water assisting in allowing said pistons in passing the dead-center.

Having thus fully described my invention, what I claim as new, and desire to secure by Letters Patent, is—

1. In a steam-pump, the combination of trunnioned steam and water cylinders, having inlet and outlet ports adapted to register with corresponding ports for admitting and exhausting steam, and admitting and discharging water from them, respectively, and pistons connected together and adapted to be moved simultaneously in opposite directions in their respective cylinders, and communicating oscillating movements thereto, substantially as and for the purpose specified.

2. In a steam-pump, the combination of trunnioned steam and water cylinders, having inlet and outlet ports adapted to register with corresponding ports for admitting and exhausting steam, and admitting and discharging wa-

ter from them, respectively, pistons adapted to move in said cylinders, and crank or similar connection provided with a fly or balance wheel, connecting said pistons together, whereby they are adapted to be moved simultaneously in opposite directions in their respective cylinders, and communicating oscillating movements thereto, substantially in the manner as and for the purpose herein shown and described.

3. In a steam-pump, the combination of the supporting-frame A, having bearing-boxes B B, provided with caps b b, and inlet and outlet ports a² a³, cylinders C D, and trunnions e d, having inlet and outlet ports a a', pistons E F, and crank G, provided with crank-pin g, to which said pistons are connected, and fly or balance wheel H, the several parts constructed and relatively arranged to operate substantially in the manner as and for the purpose herein shown and described.

In testimony whereof I affix my signature in presence of two witnesses.

GEORGE B. N. TOWER.
